HAT ORNAMENT OR THE LIKE

Anthony Dispensa, Hinsdale, Ill.

Application May 3, 1951, Serial No. 15,053

Term of patent 14 years

(Cl. D3—13)

To all whom it may concern:

Be it known that I, Anthony Dispensa, a citizen of the United States, residing at Hinsdale, in the county of DuPage, and State of Illinois, have invented a new, original, and ornamental Design for a Hat Ornament or the Like, of which the following is a specification, reference being had to the accompanying drawing, forming part thereof.

Figs. 2 and 3 are front and side views respectively thereof.

I claim:

The ornamental design for a hat ornament or the like, as shown.

ANTHONY DISPENSA.
